UNITED STATES PATENT OFFICE.

THOMAS ZIMMERMAN, OF NIAGARA FALLS, NEW YORK, ASSIGNOR TO U. S. LIGHT & HEAT CORPORATION, OF NIAGARA FALLS, NEW YORK, A CORPORATION OF NEW YORK.

SWITCH.

1,362,662.

Specification of Letters Patent. Patented Dec. 21, 1920.

Application filed December 13, 1915. Serial No. 66,568.

To all whom it may concern:

Be it known that I, THOMAS ZIMMERMAN, a citizen of the United States, residing at Niagara Falls, in the county of Niagara and State of New York, have invented new and useful Improvements in Switches, of which the following is a specification.

This invention relates to switches.

One of the objects of the invention is to provide a simple and reliable switch having a snap action in opening and closing, which snap action is irrespective of the character of the pressure applied by the operator.

Another object of the invention is to provide a switch that may be readily manufactured and assembled.

Another object is to provide an improved switch structure wherein the making and breaking arcs, if any, are drawn across parts which are not in the main current-carrying circuit.

Other objects will be apparent from the description which follows.

In the drawings, wherein is shown one of the various possible embodiments of the invention,—

Figure 1 is a sectional view showing the switch in open position.

Fig. 2 is a similar view showing the switch closed.

The present embodiment of the invention includes a block 10 of suitable insulating material. Firmly secured within said block is the bushing 11 which carries the plunger 12. Carried by the block 10 is an annular member 13, arranged concentrically with the plunger 12 and having converging walls as shown. The annular member 13 may be a complete annulus of conducting material or, if preferred, may be made up of sections of conducting material separated by insulating portions, thus providing a plurality of contacts. Opposed to the annular member 13 are the external contacts 14 and 15 the internal contact 15, which are movably mounted and are carried by means which will presently be described. The contacts 14 and 15 are annular in form and are preferably slotted to permit good spring engagement of said contacts 14 and 15 with the annular member 13. Mounted in the block 10 is a fixed auxiliary contact 16, preferably a carbon block, in electrical contact with the annular member 13. Opposed to the contact 16 is a movable auxiliary con-

tact 17, preferably of carbon, which is in good electrical connection with the contacts 14 and 15. Said contact 17 is yieldingly mounted by means of the spring 18, on the support 19, of some good conducting metal, which support 19 is in contact and moves with the contact 14. Good electrical connection between the auxiliary contact 17 and the support is assured by the pig-tail connection 20.

A spring box 21 has an extended neck portion 22 encircling and sliding upon the bushing 11. Firmly secured to the spring box 21 by any suitable means, is the contact base 23, which carries the contacts 14, 15 and the support 19. Suitably mounted in a transverse hole in the contact base 23 is a spring 24, which urges a steel ball 25 inwardly. Said ball 25 is adapted to ride in an aperture 26 in the neck portion 22, and in either aperture 27 or aperture 28. The plunger 12 is provided with a reduced central portion 29, which reduced portion has cam shaped ends 30 and 31. The parts are so proportioned that when the ball 25 is resting upon the reduced portion 29, its center will be approximately flush with the sliding surface between the bushing 11 and the neck 22. In such a position the ball 25 therefore acts as a stop to prevent relative movement between said parts.

Mounted within the spring box 21 are three coil springs 32, 33 and 34, arranged coaxially with the plunger 12. Closing the spring box at the right hand end is a cap 35. Surrounding the plunger 12 and abutting against a shoulder 36 of the same is a sleeve 37. This sleeve extends through the cap 35, as shown, and is provided with an integral collar 38 to abut against said cap 35. Said collar 38 serves as an abutment for springs 32 and 33 at their right hand ends. Spring 32 abuts against the inside of the spring box at its left hand end, whereas springs 33 and 34 at their left hand ends abut against the stationary spring support 39, which preferably assumes the shape of an annular cup. Said spring support 39 abuts against the right hand end of the bushing 11. The right hand end of spring 33 abuts against the collar 38 of the sleeve 37, while the right hand end of spring 34 abuts against a shoulder 40 on the plunger 12. A sleeve 41 is securely fastened to the left hand end of the plunger 12, which, by 110

abutting against the block 10, limits movement of the plunger 12 in a right hand direction.

A mode of operation of the above described embodiment of the present invention is as follows: The switch is shown in its open position in Fig. 1. If the operator desires to close the switch, he pushes the plunger 12 in a left hand direction, which 10 will compress springs 32, 33 and 34. As long as the ball 25 rides against the reduced portion 29 of the plunger, said ball will act as a stop to prevent relative movement between the bushing 11 and the spring box 21. When, however, the plunger is pushed far enough to the left to bring the cam shaped surface 31 in contact with the ball 25, said ball will be pushed outwardly, so that it no longer acts as a stop to prevent 20 relative movement between the bushing 11 and the spring box 21. The spring box 21, with its attached parts, including the contact base 23, the contact rings 14, 15, and the contact 17, will be suddenly snapped to 25 the left by the spring 32. This will result in the sudden closing of the switch, the parts being in the position shown in Fig. 2. The ball 25 has ridden along the bushing 11 and has dropped into the aperture 28 30 again coming into contact with the reduced portion 29 of the plunger. This position will be maintained as long as pressure is applied to the plunger 12 in a direction to push it to the left. It will be noted that 35 though the spring 32 has expended its energy, the springs 33 and 34 are still under compression. As long as plunger 12 is held in its left hand position, the ball 25 will prevent relative movement between the 40 bushing 11 and the spring box 21, with its attached parts, so that the switch is held securely closed. When the operator removes pressure from the plunger, the spring 34, exerting pressure between the fixed bush- 45 ing 11 and the shoulder 40 on the plunger, will move the plunger to the right, bringing the cam shaped portion 30 into engagement with the ball 25. The ball will be pushed outwardly and the spring 33 will 50 suddenly snap the spring box 21, with its attached parts, to the right, opening the switch. The ball 25 will ride over the bushing 11, dropping once more into the aperture 27 into engagement with the reduced 55 portion 29 of the plunger, so that the switch is securely held in its open position.

It is to be noted that the carbon contacts 16, 17, close a parallel circuit with the contacts 13, 14, 15. By reason of this construction, any sparking which occurs upon closing or opening the switch, will take place across the carbon contacts 16, 17, thus saving the main current-carrying contacts from impairment. By reason of the fact that the 65 carbon contact 17 is yieldingly mounted on

the support 19, it may be made to close contact with 16 before and open contact after the contacts 13, 14, 15, have engaged or disengaged.

One embodiment of the present invention 70 has been described in detail, but it is obvious that many changes may be made by those skilled in the art, without departing from the spirit of the invention, as defined by the appended claims. 75

What I claim as new and desire to secure by Letters Patent of the United States is:—

1. In a switch, in combination, a fixed contact support, a contact arranged thereon, a carrier having a contact, said carrier comprising a movable sleeve, a spring-pressed roller adapted to abut said sleeve alternately to lock the carrier in different positions, a plurality of mutually unopposed spring means reacting against said sleeve, one of said means being adapted to urge said sleeve in one direction, another of said spring means being adapted to urge said sleeve in the opposite direction, and a plunger movable to cause compression of 90 the spring means.

2. In a switch, in combination, a fixed contact support, a contact arranged thereon, a carrier having a contact, said carrier comprising a movable sleeve, a spring-pressed roller adapted to abut said sleeve alternately to lock the carrier in different positions, a plurality of mutually unopposed spring means reacting against said sleeve, and a plunger movable to cause compression of the spring means and operate said roller. 95

3. In a switch, a fixed contact, a longitudinally movable contact, a plurality of mutually unopposed spring means one of which is adapted to urge said movable contact in one direction and another of which is adapted to urge said movable contact in the opposite direction, said spring means being coaxial and arranged one within another, a 110 plunger co-operatively associated with said spring means to store energy therein, a spring-pressed latch co-operating with said plunger and adapted to prevent engagement or disengagement with the contacts 115 until a predetermined movement of said plunger.

4. In a switch, a fixed contact, a plunger, a plurality of mutually unopposed energy storing means associated with said plunger, 120 a fixed member associated with said plunger provided with a pair of spaced apertures, movable contact-carrying means provided with a spring-pressed latching member adapted to fit within one or the other of 125 said apertures, said plunger being provided with latch-engaging portions to move said latch to permit the energy storing means to move said movable contact carrying means with a snap action, one of said energy stor- 130

ing means being adapted to urge said movable contact-carrying means in one direction, another of said energy-storing means being adapted to urge said movable contact-carrying means in the opposite direction and another of said energy-storing means being adapted to bias said plunger.

5. In a switch, a fixed contact, a plunger, a fixed member associated with said plunger, a movable contact carrying member provided with a spring-pressed latching member, which latching member cooperates with said fixed member to hold said movable contact-carrying member in either 15 of two positions, said plunger being provided with cam shaped portions to engage said latching member, and a plurality of mutually unopposed energy storing means, one of said energy-storing means being 20 adapted to urge said movable contact-carrying member in one direction, another of said energy-storing means being adapted to urge said movable contact-carrying member in the opposite direction and another of said 25 energy-storing means being adapted to bias said plunger.

6. In a switch, a fixed contact, a movable contact, a latch for holding said movable contact in either open or closed position, controlling means for said latch, energy-storing means for urging said movable contact to closed position, energy-storing means for urging said movable contact to open position, and energy-storing means for biasing 35 said controlling means to a certain position, said energy storing means being mutually unopposed springs which are mounted coaxially.

7. In a switch, a fixed contact, a movable contact, means for holding said movable contact in either open or closed position, controlling means for said holding means, a coil spring for urging said movable contact to closed position, a coil spring for 45 urging said movable contact to open position, and a coil spring for biasing said controlling means to a certain position, said springs being coaxially arranged within one another and mutually unopposed.

50 8. In a switch, a manually operable plunger provided with a reduced portion and cam shaped portions intermediate its length, a fixed member provided with a pair of apertures adjacent said plunger, a 55 contact-carrying member mounted adjacent said fixed member, said contact-carrying member being provided with an aperture to register with one or the other of said pair of apertures, a spring-pressed ball carried by said contact-carrying member riding in the aperture in said contact-carrying member and adapted to project through one or the other of said pair of apertures to engage said reduced portion of the 60 plunger to lock the contact carrying mem-

ber against movement, the said cam shaped portions being adapted to move said ball to permit movement of said contact carrying member, energy storing means for biasing said plunger to an outward position, 70 energy storing means for urging said contact carrying means in one direction, and energy storing means for urging said contact-carrying means in the opposite direction.

75 9. In a switch, a manually operable plunger provided with a reduced portion and cam shaped portions intermediate its length, a fixed member provided with a pair of apertures adjacent said plunger, a 80 contact-carrying member mounted adjacent said fixed member, said contact-carrying member being provided with an aperture to register with one or the other of said pair of apertures, a spring-pressed ball carried 85 by said contact-carrying member riding in the aperture in said contact-carrying member and adapted to project through one or the other of said pair of apertures to engage said reduced portion of the plunger 90 to lock the contact-carrying member against movement, the said cam shaped portions being adapted to move said ball to permit movement of said contact carrying member, energy storing means for biasing said 95 plunger to an outward position, energy storing means for urging said contact carrying means in one direction, and energy storing means for urging said contact carrying means in the opposite direction, said energy 100 storing means being superposed.

10. In a switch, a fixed contact, a movable contact, means for causing movement of said movable contact, locking means adapted to lock said movable contact in two different positions controlled by said first-named means, a spring for suddenly moving said movable contact when the same is unlocked, a spring for suddenly moving said movable contact in the reverse direction 110 when the same is unlocked, and a spring for biasing said manual means to a certain position, said springs being coaxially arranged within one another and mutually unopposed.

115 11. In a quick acting make and break switch, a fixed member provided with a pair of apertures, a movable member slidable thereon provided with an aperture adapted to register with one or the other of said pair of apertures, a plunger provided with a reduced central portion, said reduced portion having cam shaped ends, a spring-pressed ball mounted in said movable member and adapted to extend through the aperture on said movable member and through one of the apertures of the fixed member to engage the reduced portion of the plunger, said parts being so proportioned 120 that when the ball rests against the said 125 plunger to lock the contact carrying mem-

reduced portion, its center will be approximately flush with the sliding surface between the fixed and movable members, whereby to prevent movement, energy storing means controlled by said plunger adapted to urge said movable member in either of two directions, whereby when one of the said cam shaped portions engages said ball to raise its center above said sliding surface the ball will be forced out of the

aperture in the fixed member and the movable member will move with a snap action until the ball engages the other aperture in the fixed member and whereby when the other cam shaped portion engages said ball ¹⁵ to raise its center, the reverse action will occur.

In witness whereof I have hereunto subscribed my name.

THOMAS ZIMMERMAN.
